UNITED STATES PATENT OFFICE.

HENRY WILLIAM CLOTHIER, OF WALLSEND-ON-TYNE, AND BRUCE HAMER LEESON, OF TYNEMOUTH, ENGLAND, ASSIGNORS TO A. REYROLLE & COMPANY LIMITED, OF HEBBURN-ON-TYNE, ENGLAND, A COMPANY REGISTERED UNDER THE LAWS OF GREAT BRITAIN.

ELECTRIC-CIRCUIT BREAKER AND THE LIKE.

Application filed March 11, 1924. Serial No. 698,503.

To all whom it may concern:

Be it known that we, HENRY WILLIAM CLOTHIER and BRUCE HAMER LEESON, subjects of the King of England, and residing, respectively, at Wallsend-on-Tyne, county of Northumberland, in England, and Tynemouth, county of Northumberland, in England, have invented certain new and useful Improvements in Electric-Circuit Breakers and the like, of which the following is a specification.

This invention relates to electric circuit breakers and the like and has particular reference to circuit breakers suitable for use on traction or other systems where short circuits are likely to occur. Such short circuits, as is well known frequently cause "flash-overs" on the commutators of direct current generators. The short circuit current probably first produces a conducting vapour on the commutator the quantity of this vapour being a function of the current and of the duration of that current. Thus to prevent these flash-overs the circuit breaker employed should keep the short circuit current low and break the circuit quickly.

These conditions are fulfilled in a circuit breaker according to this invention which is furnished with series and shunt windings, the series winding tending to open the contacts and the shunt winding to keep them closed. Preferably the windings are on separate magnetic circuits and act on a movable armature common to both circuits, the series coils carrying the main current and the shunt coils being connected say across the terminals of the D. C. generator. Under normal load conditions the shunt coil and its core act as a holding electromagnet and retain the armature in such a position as to keep the contacts closed. This retaining or holding action is against the force exerted by the series coils and also preferably against the action of auxiliary springs which tend to open the contacts.

When a short circuit occurs the voltage across the shunt coil drops and the holding electromagnet releases the armature. At the same time the current in the series coil rises and exerts an increased pull on the armature. As the armature moves away from the shunt wound magnet, the force ex-

erted by that magnet will decrease as the square of the distance between the armature and the magnet pole. Further the pull due to the series magnet will increase in the same proportion for constant current but also, as above mentioned the current is increasing in the series coils and, depending to some extent on the density of flux in the iron, the pull due to the series coils will increase in proportion to the square of the current. It will thus be seen that the opening action of the circuit breaker is very rapid.

There is also another important effect. As above mentioned the movable armature is common to the two magnetic circuits and the poles of the two electromagnets are so arranged that the fluxes through the armature are in the same direction. Now before the armature moves the flux in it due to the shunt winding will decrease as soon as the voltage drops. This has the effect of increasing the flux due to the series coils or in other words of introducing reactance into the series circuit. The importance of this feature is due to the fact that the reactance introduced retards the growth of the short circuit current in its first stages, i. e., before the mechanical operation of the breaker begins. In other words the initial slope or steepness of the current-time curve of the short circuit current is reduced and time is given for the mechanical portions of the mechanism to accelerate and open the contacts before the short circuit current reaches the maximum value which it would otherwise have attained.

In the accompanying drawings—

Figure 1 is a front view showing diagrammatically the essential parts of one construction of circuit breaker according to this invention, and

Figure 2 is a side view.

Figure 3 is a diagram showing by way of example how the improved circuit breaker may be used on a system supplying power for traction purposes.

With reference first to Figures 1 and 2. In a suitable framework (not shown in the drawings) two magnetic cores A and B are supported, the poles of the two U's being separated by a gap in which a more or less rectangular armature C can move up and down the armature thus being capable of

acting as a keeper to each of the cores A and B. The armature is pivoted at C' (Figure 2) on a horizontal shaft at one side of the apparatus and the top and bottom surfaces of the armature are shaped so that the upper surface is parallel to and in close proximity with the poles of the upper core A when the armature is in its raised position and the lower surface of the armature is in similar relationship with the poles of the lower core B when the armature is in its bottom position as shown in the figures.

The upper magnetic core A carries the series winding D and the lower magnetic core B is excited by a shunt or potential winding E. The upper member or yoke of the core A is divided and in the gap the main contacts F and F' are placed. These contacts may be of any suitable form but are preferably provided with main and sparking contacts F² F³ of the kind described in the specification of British Letters Patent No. 167,846. Conveniently the main contact F' is fixed and the other main contact F is mounted on a spindle G which can be rocked to open the contacts. It will be understood that the object of placing these contacts in a gap in the upper magnetic circuit is to cause the opening of the contacts to take place in a strong magnetic field which tends to blow out the arc between the sparking contacts. The rocking of the spindle G carrying the movable contact F is brought about by means of links or connecting rods H joined between crank arms H' on the spindle G and arms C² fixed to the armature C. These rods or links H are provided with springs H² which tend to keep the armature C against the poles of the series magnet core A in which position the contacts would be open as indicated in chain lines in Figure 2. Preferably a dash-pot C³ is provided to relieve the mechanical shock due to the high velocity of the armature and its connected parts.

The shunt or potential winding E on the lower or holding magnet core B may be in two or more parts or may be tapped and connected to a switch arm or rheostat so that the current in the winding E may be regulated. As shown in Figure 2 this regulation is effected by a switch arm J controlling a stepped resistance J' in series with the winding E. An additional coil may be provided on this shunt or holding magnet B, this winding being indicated at E'. This additional winding E' may be used to close the contacts, that is to say, to pull the armature down on to the magnet core B after it has been raised to open the contacts.

Although the improved apparatus is termed a contact breaker and is adapted for use as such, it is to be understood that the separation of the contacts F F' need not necessarily break the circuit entirely. The

apparatus may function for instance as a current diverter rather than a circuit breaker. This may be provided for by joining a limiting resistance K across the contacts F and F' as shown diagrammatically in Figure 2. 70 This resistance K may be graded or stepped and may be controlled by a switch K' operated by the movement of the armature C. Such an arrangement is useful when the improved circuit breaker is employed in conjunction 75 with some known form of switch or circuit breaker operating comparatively slowly. When thus employed the high speed circuit breaker according to this invention does not finally break the circuit but it takes the 80 stress produced by the short circuit current, it retards the growth of that current and protects the generator and then when the graded limiting resistance above referred to is employed it cuts out the current progressively before the circuit is finally interrupted by the trip mechanism of an ordinary circuit breaker.

The diagram forming Figure 3 is merely given to show by way of example how the 90 improved circuit breaker or current diverter may be used in connection with a system supplying current for traction purposes. In this diagram L L' are the bus-bars, M is a rotary or motor generator which is to 95 be protected by the circuit breaker and N and N' represent the track and live rail respectively. Those parts of the circuit breaker or current diverter which are shown in Figure 3 are lettered to correspond with 100 the corresponding parts in Figures 1 and 2. In Figure 3, O is an ordinary slow speed circuit breaker controlling the main connection to the bus-bar L' and P is a slow speed feeder circuit breaker controlling the connection from the bus-bar L' to the live rail N' but provided with auxiliary contacts P' which control the closing coil E' of the circuit breaker or current diverter. In this arrangement the main contacts F F' of the circuit breaker are closed automatically by the action of the coils E and E' as soon as the feeder circuit breaker P has opened the faulty feeder which it controls, provided that the voltage of the generator M has 110 risen again to the normal.

Referring again to Figures 1 and 2 it is to be understood that the winding of the series coil D and the potential coil E is such that the flux from the core A tends to pass 120 through the armature C in the same direction as the flux from the core B. Thus supposing the armature C to be held down by the holding or potential coil E as shown in the figures, then a weakening of the flux from the core B due to a decrease of current in the winding E will cause or allow an increase of the flux in the core A. This increases the reactance of the series winding D and tends to retard the growth of the 130

current in that winding due to a short circuit or overload.

Although in Figure 2 the graded resistance K across the main contacts F F' is shown as controlled directly by a switch arm moved by the armature, it is to be understood that the movement of the armature may control this graded resistance indirectly through appropriate circuits with local contact makers.

What we claim as our invention and desire to secure by Letters Patent is:—

1. In an electromagnetic circuit-controlling device, the combination of two magnetic cores or circuits, an armature movable in a gap between such cores, a switch operated by the movement of the armature, a series winding on one magnetic core tending to move the armature so as to open the switch, and a shunt winding on the other magnetic core tending to hold the armature so as to keep the switch closed, the series and shunt windings being so arranged that the magnetic fluxes due to currents in them pass through the armature in the same direction so that weakening of the flux due to a decrease of current in the shunt winding causes an increase of the flux in the magnetic circuit of the series winding and consequently increases the reactance of that winding and tends to retard the growth of the current in that winding due to a short circuit or overload.

2. In an electromagnetic circuit-controlling device, the combination of two U-shaped magnetic cores having their similar poles separated by an air gap, one of such cores having a second air gap in its yoke, an armature movable in the air gap between the poles, a switch operated by the movement of the armature, a series winding on the U-shaped core which is provided with the second air gap, said winding having sufficient ampere-turns to overcome the reluctance of said air gap and move the armature to open the switch where an overload occurs, and a shunt winding on the other magnetic core tending to hold the armature so as to keep the switch closed.

3. In an electromagnetic circuit-controlling device, the combination of two U-shaped magnetic cores having their similar poles separated by an air gap, one of such cores having a second air gap in its yoke, an armature movable in the air gap between the poles, a switch placed in the second air gap and operated by the movement of the armature, a series winding on the U-shaped core which is provided with the second air gap, said winding having sufficient ampere-turns

to overcome the reluctance of said air gap and move the armature to open the switch where an overload occurs, and a shunt winding on the other magnetic core tending to hold the armature so as to keep the switch closed.

4. In an electromagnetic circuit-controlling device, the combination of two U-shaped magnetic cores having their similar poles separated by an air gap, one of such cores having a second air gap in its yoke, an armature movable in the air gap between the poles, a switch placed in the second gap and operated by the movement of the armature, a limiting resistance across the contacts of said switch, a series winding on the U-shaped core which is provided with the second air gap, said winding having sufficient ampere-turns to overcome the reluctance of said air gap and move the armature to open the switch where an overload occurs, and a shunt winding on the other magnetic core tending to hold the armature so as to keep the switch closed.

5. In an electromagnetic circuit-controlling device, the combination of two U-shaped magnetic cores having their similar poles separated by an air gap, one of such cores having a second air gap in its yoke, an armature movable in the air gap between the poles, a switch operated by the movement of the armature, a series winding on the U-shaped core which is provided with the second air gap, said winding having sufficient ampere-turns to overcome the reluctance of said air gap and move the armature to open the switch where an overload occurs, a shunt winding on the other magnetic core tending to hold the armature so as to keep the switch closed and a regulating resistance and switch in said shunt winding.

6. In an electromagnetic circuit-controlling device, the combination of two magnetic cores or circuits, an armature movable in a gap between such cores, a switch operated by the movement of the armature, a series winding on one magnetic core tending to move the armature so as to open the switch, a shunt winding on the other magnetic core tending to hold the armature so as to keep the switch closed, and an additional winding on the shunt-wound magnetic core for use in moving the armature back after it has been moved by the action of the series winding.

In testimony whereof we have signed our names to this specification.

HENRY WILLIAM CLOTHIER.
BRUCE HAMER LEESON.
